UNITED STATES PATENT OFFICE.

GARTH G. GILPIN, OF RIVERSIDE, ILLINOIS, ASSIGNOR TO UNION METAL PRODUCTS COMPANY, OF CHICAGO, ILLINOIS, A CORPORATION OF DELAWARE.

UNCOUPLING DEVICE FOR CAR COUPLERS.

Original application filed July 12, 1923, Serial No. 651,151. Divided and this application filed January 6, 1926. Serial No. 79,555.

This particular invention relates to what is generally known in the art as the push down or vertical plane type of uncoupling device and comprises two levers operatively connected having their adjacent ends pivotally mounted on the same fulcrum. Such devices are operated either by hand or foot. (The particular advantage of this construction resides in the manner in which the 10 levers are pivoted upon the fulcrum.) In levers of this general type the connection between the levers must allow the pin lifting lever to move freely laterally to accommodate the longitudinal movement of the coupler in draft and in buffing.

The manner of operatively mounting the pin lifting lever upon the operating lever in accordance with this invention permits it to move or swing laterally to accommodate the movements of the coupler in buff and draft and the manner of mounting the operating lever upon the fulcrum prevents or restricts its moving or swinging laterally in a horizontal plane, so that the lateral or pivotal movement of the pin lifting lever cannot be transmitted to the operating lever. The manner of mounting the pin lifting lever upon the operating lever prevents it from tipping and binding, thereby causing 30 friction in the device.

The impact of coupling causes sudden longitudinal movement of the coupler, which movement is transmitted to the adjacent end of the pin lifting lever and would be transmitted to the operating lever unless that lever is prevented from moving laterally. Switchmen frequently ride a moving car while coupling it and at the same time signal the engineer. In such an act he usually 35 holds on the grab iron with his left hand and signals the engineer with his right hand while his left foot is on the sill step and his right foot is on the operating lever. While in such a position a sudden movement of the operating lever has a tendency to, and frequently does, throw him from the car. One of the objects, therefore, is to provide 40 a device which is safe for the switchman to operate.

The return bend and the extended portion therefrom provides two bearings which are provided in parts of the same metallic bar, therefore, act in unison to increase the bearing area of the operating lever upon the ful-

crum, prevent or restrict it from moving or 55 swinging laterally and prevent it from tipping from a vertical plane.

Good practice requires that the handle end of the operating lever be positioned slightly in front of the vertical plane of the face of 60 the end sill and below the push pole pocket. This is a generally recognized location of this handle, therefore, switchmen can reach it quickly even in the darkness. It is advantageous, therefore, to not permit the 65 lever to move laterally, and especially advantageous not to allow the sudden or jerky movement of the pin lifting lever to be transmitted to the operating lever.

Means are provided to restrict the movement of the lever in a vertical plane which is a requirement of the Interstate Commerce Commission safety appliance acts.

A separate connecting member and bearing block has the advantages of increasing 75 the bearing area on the journal fulcrum thereby reducing the friction and making the device easier to operate and also reducing the wear on the associated parts. The connecting block non-rotatively connects the 80 operating lever and the pin lifting lever so that a force exerted on the outer end of the operating lever raises the inner end of the pin lifting lever.

In the drawings:

Fig. 1 is a perspective view of a car with my invention applied thereon.

Fig. 2 is an enlarged detail of the fulcrum.

Fig. 3 shows the relation of the fulcrum, 90 member and levers.

Fig. 4 is an elevation of Fig. 3.

Fig. 5 is a plan view of the fulcrum end of the operating lever.

Fig. 6 is an elevation of Fig. 5.

Figs. 7 and 8 are views of the separate member introduced between the operating lever and the fulcrum.

The usual parts of the car are shown, such as the end sill 1; the push pole pocket 2; the 100 coupler 3; the lock lifter 4; the striking casting 5 and the carry iron 6.

The operating lever 30 is mounted on fulcrum 8 and the pin lifting lever 37 is mounted on the operating lever 30. This pin 105 lifting lever is operatively connected to the lock lifter 4 of the coupler 3. The operating lever 30 is extended toward the side of

the car to any convenient location so that it can be operated by hand or foot. A downward pressure on the end 10 of the operating lever 30 raises the lock lifter 4 of the coupler. The lock is thus raised from behind the tail of the knuckle which permits the knuckle to swing outwardly and uncouple the cars; in fact, the raising of the lock automatically throws the knuckle. This, however, is within the head of the coupler and has nothing to do with this invention.

The operating lever 30 is provided with a rebent portion 31 and extended to form portion 32. The main part 30 and the portion 32 is provided with apertures 33 and 34 respectively through which connecting and bearing block 35 is inserted and the bearing block 35 with the two levers mounted thereon are then mounted upon journal 15 of the fulcrum 8. A non-rotative connection is provided between the operating lever 30 and the connecting block 35 by the peculiar contour of the apertures 33 and 35 which coincide with the exterior perimeter of connecting block 35.

The connecting block 35 has projections 36 which engage stops 19 and 20 of fulcrum 8 to limit its rotation in a vertical plane which automatically limits the rotation of levers 30 and 37. The horizontal distance between the connecting block 35 and the rebent portion 31 is only slightly greater than portion 21 of the pin lifting lever which prevents the pin lifting lever from tipping and wabbling.

The parts are held in operative relation by bolt 38 with its washer 39 and nut 40.

This is a division of my co-pending application Serial No. 651,151, filed July 12, 1923.

40 I claim:

1. An uncoupling device for car couplers comprising an operating lever provided with an aperture, said lever rebent to form a portion provided with an aperture, a member passing through said apertures having a non-rotative connection therewith, a fulcrum passing through said member having a rotative connection therewith, and a pin lifting lever operatively mounted on said operating lever.

2. An uncoupling device for car couplers comprising an operating lever provided with an aperture, said lever rebent to form a portion provided with an aperture, a mem-

ber passing through said apertures having a non-rotative connection therewith, a fulcrum passing through said member having a rotative connection therewith, and a pin lifting lever operatively mounted on said operating lever, said member and fulcrum each provided with means which co-act to restrict the movement of the operating lever in a vertical plane.

3. An uncoupling device for car couplers comprising an operating lever provided with an aperture, said lever rebent to form a portion provided with an aperture, a member passing through said apertures having a non-rotative connection therewith, a fulcrum passing through said member having a rotative connection therewith, and a pin lifting lever operatively mounted on said operating lever, said member and fulcrum each provided with means which co-act to restrict the movement of the operating lever in a vertical plane both upwardly and downwardly.

4. An uncoupling device for car couplers comprising an operating lever provided with an aperture, said lever rebent to form a portion provided with an aperture, a member passing through said apertures having a non-rotative connection with one of said apertures, a fulcrum passing through said member having a rotative connection therewith, and a pin lifting lever operatively mounted on said operating lever.

5. An uncoupling device for car couplers comprising a fulcrum, a member rotatively mounted upon said fulcrum, an operating lever non-rotatively mounted on said member, said lever having a return bend at its fulcrum end extended to provide a double bearing on said member so as to restrict the lateral swing of said lever, and a pin lifting lever mounted on said bend.

6. An uncoupling device for car couplers comprising a fulcrum, a member rotatively mounted upon said fulcrum, an operating lever non-rotatively mounted on said member, said lever having a return bend at its fulcrum end extended to provide a double bearing on said member so as to restrict the lateral swing of said lever, and a pin lifting lever mounted on said bend so as to hold it in substantially vertical position.

GARTH G. GILPIN.
